UNITED STATES PATENT OFFICE.

ALPHONSO DAVINO, OF SAN DIEGO, CALIFORNIA.

CABLE-CONTROLLED CARRYING APPARATUS.

1,226,314.

Specification of Letters Patent. Patented May 15, 1917.

Application filed May 1, 1916. Serial No. 94,583.

To all whom it may concern:

Be it known that I, ALPHONSO DAVINO, a citizen of the United States, residing at San Diego, in the county of San Diego and State 5 of California, have invented certain new and useful Improvements in Cable-Controlled Carrying Apparatus, of which the following is a specification.

My invention relates to an apparatus for carrying purposes which is preferably in the form of an aeroplane carrying device suspended upon a supporting cable by other cables and adapted to be raised and lowered between said supporting cable and the earth 15 as desired, and the objects of my invention are: First, to provide an apparatus of this class with means for controlling the position of the carrying device relatively to the supporting cable; second, to provide for an 20 automatic control for balancing the same so as to provide for its equilibrium; third, to provide for electrical control of a portion of the apparatus; fourth, to provide a new and novel cable carriage and cable 25 support; fifth, to provide an apparatus to assist students beginning to learn aviation, and sixth, to provide an apparatus of this class which is simple, durable, economical 30 of construction, safe, will not readily get out of order and inexpensive to operate.

With these and other objects in view as will appear hereinafter, my invention consists of certain novel features of construction, combination and arrangement of parts 35 as will be hereinafter described in detail and more particularly set forth in the appended claims, reference being had to the accompanying drawings and to the characters of reference thereon which form a part of this 40 specification, in which:

Figure 1 is a longitudinal sectional view of the carrying device portion of my apparatus and showing the cable carriage in elevation to facilitate the illustration. Fig. 45 2 is a side elevational view of a gyroscope and directly connected motor for operating the same shown incased and with a portion thereof in engagement with a rheostat bar. Fig. 3 is a similar view at right angles 50 thereto. Fig. 4 is a fragmentary side elevational view of the cable carriage. Fig. 5 is a sectional view through A—B of Fig. 1. Fig. 6 is a sectional view through C—D of Fig. 1. Fig. 7 is a perspective view of the 55 cable support showing the cables mounted thereon. Fig. 8 is a front elevational view

of the cable support. Fig. 9 is a side elevational view thereof, and Fig. 10 is a top view showing the cable carriage wheels approaching the cable support.

66

Similar characters of reference refer to similar parts throughout the several views. The carrying device body 1, propeller 2, motor 3, rheostat 4, drum 5, motor 6, drum 7, motor 8, rheostat 9, gyroscope and motor 65 10, plane 11, drum 12, motor 13, conductor cables 14, suspension cables 15, and 16, carriage frame 17, upper supporting wheels 18, locking wheels 19, trolley wheels 20, supporting cable 21, and conducting cable 22, 70 75 constitute the principal parts of my apparatus.

The vehicle body 1 is preferably canoe-shaped as shown best in Fig. 1 of the drawings, provided with a sub-floor 1^a therein 75 upon which is mounted a plurality of seats 1^b. Mounted between the sub-floor 1^a and the bottom of the boat in the middle thereof and secured to said boat bottom, is the drum 5 which is directly connected to the motor 6 80 and spaced apart therefrom some distance back in the middle of said boat, is another drum 7 which is directly connected to the motor 8. Adjacent the drum 7 is a rheostat 9 mounted immediately beneath one of the 85 seats, and pivotally mounted between the supporting members of said seat is the gyroscope and its operating motor in a casing 10, 90 which is provided with an extending member 10^a which engages with the bar of rheostat 9 at its lower end. Mounted on the drum 5 is a pair of cables 15 which extend upwardly through the plane 11 where they are 95 spaced apart from each other, and they are secured to the lower end of the support 17^a 95 on the carriage frame 17, as shown best in Figs. 1 and 5. Mounted on the drum 7 is a pair of cables 16 which extend upwardly through the plane 11 where they are spaced apart from each other, and they are secured to the lower end of the support 17^b on the frame 17. The carrying device body 1 is supported on the ground when resting thereon by means of wheels 1^c, mounted on supports 1^d. Mounted in the front end of the vehicle body 1 is the motor 3, to which is secured the propeller shaft 2^a upon the outwardly extended end of which is secured the propeller 2. This motor 3 is controlled by the operator in the conventional way. Mounted in front of the operator is a rheostat 4 which is electrically connected to the

100
105
110

motor 6 for controlling said motor 6. It will be here noted that all the motors, including 3, 6, 8 and 13, receive their electrical energy through the conducting cable 22 and the supporting cable 21, and the conducting cables 14 connect with the trolley wheels 20 which conduct the current to the various motors through their rheostats.

It will be here noted that the vehicle body 1 is raised and lowered by the cables 15 and 16 being wound and unwound on the drums 5 and 7, that the drum 5 and motor 6 are manually controlled by the rheostat 4, and the drum 7 and motor 8 are automatically controlled by the gyroscope in connection with the rheostat 9. The gyroscope 10 and rheostat 9 synchronize the motor 8 with the motor 6 so that the body of the vehicle is supported in equilibrium at all times as the cables 15 and 16 wind evenly on the drums 5 and 7.

The objects of the drum 12 and motor 13 are for the purpose of keeping the circuit conducting wire 14 taut at all times. The cable carriage consists of a frame 17, shaped as shown best in Figs. 1, 4, 5 and 6 of the drawings. The four upper wheels 18 are revolvably mounted on the frame 17 and are provided with grooves 18a adapted to ride on the cable 21. The wheels 19 are similarly constructed and are adapted to ride below said cable and normally engage with the lower surface thereof, as shown in Fig. 6 of the drawings, however when the wheels 19 come to the cable supports 21a, said wheels 19 are shifted sidewise as shown in Figs. 5 and 10 of the drawings by means of the angled pieces 21b as shown in Fig. 10, and, after passing by the said pieces 21b, are returned to their positions immediately below the wire 21 by the pressure of the coiled springs 19b. These wheels 19 prevent the wheels 18 from leaving this cable 21. The trolley wheels 20 travel on opposite sides of the conducting cable 22 and conduct the electrical current to the various motors through the wires 14, as hereinbefore set forth.

Though I have shown and described a particular construction, combination and arrangement of parts, I do not wish to be limited to this particular construction, combination and arrangement, but desire to include in the purview of my invention, the construction, combination and arrangement substantially as set forth in the appended claims.

It is obvious that with the above apparatus, there is provided a cable controlled carrying device in the form of an aeroplane, which carrying device may be readily raised and lowered from the ground to a position near the cables, and to the ground, as desired, that said carrying device will be moved along the cable by means of the pro-

peller 2 and controlled by means of motors, that the vehicle is raised and lowered in a normally horizontal position by means of the synchronizing of the motor 8 with the motor 6 by means of the gyroscope operating the rheostat control of said motor 8, that the motors receive their source of electrical energy from the cables 21, and 22 and the lead wires 14 from the trolley 21 engaging with the wire 22, that the particular construction of carriage and cable supports provides a safety device whereby the cable carriage is held in position on the cables, that the apparatus as a whole is safe, durable and easy to operate.

Having thus described my invention, what I claim as new and desire to secure by Letters Patent, is:

1. In an apparatus of the class described, a pair of electric circuit carrying cables, a carriage mounted on said cables, a carriage in the form of an aeroplane suspended from said first mentioned carriage by means of cables and drums upon which said cables are wound, secured to said last mentioned carriage, means for manually operating some of said drums and means for synchronizing other of said drums with said first mentioned drums.

2. In an apparatus of the class described, a pair of electric circuit carrying cables, a carriage mounted on said cables, a carriage in the form of an aeroplane suspended from said carriage by means of cables, drums upon which said cables are wound secured to said vehicle, means for manually operating some of said drums, means for synchronizing other of said drums with said first mentioned drums and a propeller mounted on said carriage for moving said carriage on said cables.

3. In an apparatus of the class described, a pair of electric circuit carrying cables, a carriage mounted on said cables, a vehicle in the form of an aeroplane suspended from said carriage by means of cables, drums upon which said cables are wound secured to said vehicle, means for manually operating some of said drums, means for synchronizing other of said drums with said first mentioned drums, a propeller mounted on said vehicle for moving said vehicle and said carriage on said cables, and means for locking said carriage on said cables.

4. In an apparatus of the class described, the combination of a supporting cable, a carriage mounted thereon, a plurality of cables suspended from said carriage, a passenger carrying device, drums revolvably mounted with their bases secured to said passenger carrying device, the one adapted to be manually operated and the other operated by means of a gyroscope operating a rheostat, whereby said drums are synchronized and said passenger carrying device

maintains its equilibrium when being raised and lowered by the winding of said cables on said drums.

5. In an apparatus of the class described, the combination of a supporting cable, a carriage mounted thereon, a plurality of cables suspended from said carriage, a passenger carrying device, drums revolubly mounted with their bases secured to said 10 passenger carrying device, the one adapted to be manually operated and the other operated by means of a gyroscope operating a rheostat, whereby said drums are synchronized and said passenger carrying device maintains its equilibrium when being raised and 15 lowered by the winding of said cables on said drums, means for propelling said passenger carrying device and means for steering said passenger carrying device.
6. In an apparatus of the class described, the combination of a supporting cable, a carriage mounted thereon, a plurality of 20

cables suspended from said carriage, a passenger carrying device, drums revolubly mounted with their bases secured to said passenger carrying device, the one adapted to be manually operated and the other operated by means of a gyroscope operating a rheostat, whereby said drums are synchronized and said passenger carrying device maintains its equilibrium when being raised and 25 lowered by the winding of said cables on said drums, means for propelling said passenger carrying device and means for steering said passenger carrying device.

In testimony whereof I have hereunto 30 subscribed my name in the presence of two subscribing witnesses.

ALPHONSO DAVINO.
